UNITED STATES PATENT OFFICE.

GEORGE C. MURRAY, OF CHICAGO, ILLINOIS.

DRAFT-RIGGING CONSTRUCTION.

1,361,087.

Specification of Letters Patent. Patented Dec. 7, 1920.

Application filed July 14, 1917. Serial No. 180,535.

To all whom it may concern:

Be it known that I, GEORGE C. MURRAY, a citizen of the United States, residing at Chicago, in the county of Cook and State of Illinois, have invented certain new and useful Improvements in Draft-Rigging Construction, of which the following is a specification.

This invention relates to improvements in draft rigging construction, and has for its object to provide an improved construction of the type shown and described in my prior Patent No. 1,224,312, patented May 1, 1917.

15 The principal object of this invention is to provide, in connection with draft rigging of that nature, improved front and back draft lugs and to provide an integral rear draft lug and center plate filler casting, also operating to tie the draft sills together.

Another object is to provide an improved front draft lug coating with an improved draw-bar which, when utilized with the type of draft rigging shown and described in the 25 above-mentioned patent, will prevent or eliminate shearing or bending action upon the front cross-key, and means to maintain the draft links in proper spaced relation with respect to the draft sills.

30 Still another object is to provide front draft lugs which will be of sufficient strength to receive sudden shocks of greater capacity than will be absorbed by the draft rigging, and capable of relieving the key of bending 35 stresses due to such excess shocks.

Still another object resides in the construction of the rear combination follower and key socket and its relation to the draft lugs.

40 These and other objects will be more fully set forth and described in the following specification and shown in the accompanying drawings, in which—

Figure 1 is a plan view partially in section of an improved draft rigging construction embodying my invention;

Fig. 2 is a vertical longitudinal section through the same;

Fig. 3 is a double sectional view along the 50 line 3—3 of Fig. 1;

Fig. 4 is a perspective of the combined rear draft lug and center plate filler casting member;

Fig. 5 is a perspective of a spacing 55 washer;

Fig. 6 is a perspective of a key housing member;

Fig. 7 is a perspective of the draw-bar;

Fig. 8 is a perspective of one of the front draft lugs; and

Fig. 9 is a perspective of one of the keys and connecting links.

Like numerals refer to like elements throughout the drawings, in which 10 designates the spaced apart draft sills of the car, 65 15 the draft rigging mounted therebetween, the specific form of which does not form a part of this invention, and 20 the draw-bar also mounted between the draft sills 10 and intended to coat with the draft rigging, as 70 will be more fully explained. Located between and riveted or otherwise suitably secured to the draft sills 10 is the member 25—shown in perspective in Fig. 4—the same comprising, in one, the rear draft lugs and a 75 center filler casting. The member 25 is provided with a recess or socket 25^a formed by the cross-channel 25^b extending across, between, and through the rear draft lugs 25^c. Extending between the side sills 25' of the 80 member 25—which side sills are riveted to the draft sills 10—is the horizontal flange 25^d and the vertical flange 25^e, which flanges serve to add rigidity and strength to the structure while permitting sufficient strength 85 with a minimum of weight. The member 25 is provided with a socket or aperture 25^f for a center pin.

It has been found in actual use that where 90 separate cross tie members are constructed with the rear draft lugs mounted between the draft sills, they must extend backwardly a sufficient distance and be secured along said distance to the draft sills to resist and provide for the buffing stresses received by 95 the draft rigging and communicated to the rear draft lug. At the same time, I have found it advisable to provide a cross tie member for the center pin casting, but this also must extend a sufficient distance in 100 either direction from the center-pin socket to take up longitudinal stresses and strains; and, in present day construction, to provide sufficient strength would require an overlapping or interference of the two members. 105 I eliminate this necessity by constructing the center plate casting and the rear draft lug and cross tie member integral, whereby sufficient riveting length is provided in the one member to take care of the longitudinal 110

stresses transmitted thereto not only by the draft rigging but by the center plate. At the same time, a considerable saving in expense and weight is effected, also in the cost 5 of assembly and manufacture.

In the patent mentioned above, I have shown and described a socket member co-acting with the rear draft lugs by which all the buffing compression was received from 10 the draft rigging between such draft rigging and the rear draft lugs. Where such member, rested upon and against the four rear draft lugs, the force of compression was exerted upon the area of the following 15 member, as stated, which contacted with the draft lugs and a comparatively small area of such follower member received the entire compression of the buffing stresses. In some instances it was restricted to the 20 area and contact of but one or two of the draft lugs, further increasing such compression, due to the warping or uneven contact of the follower member. I overcome 25 this objection in the present construction by providing the key housing member indicated by numeral 30 and shown in detail in Fig. 6, this member being provided with a rearwardly extending portion 30^a through 30 which extends the key aperture 30^b. This member 30 is further provided with a front 35 face or portion 30^c cut away at its corners or notched as indicated by numeral 30^d. Strengthening ribs or flanges 30^e extend between the rear of the portion 30^c and the 40 socket portion 30^a to insure rigidity and strength. When in assembled relation, as 45 shown in Figs. 1, 2, and 3, the socket portion 30^a of member 30 fits into the cavity or socket 25^a of member 25 when in normal 50 position in such wise that the cut-out portions 30^c of member 30 permit the assumption of a position by member 30 whereby the front surface of follower 30^c will lie substantially flush with the front face of 55 the draft lugs 25^c, so that the buffing stress transmitted by the rear follower member 15^a of the draft rigging will be transmitted over substantially the full area of the key housing member 30^c and the draft lugs 25^c 60 in such wise that there will be no portion of the member 30 compressed between the follower member 15^a and the draft lugs 25^c, as will be obvious.

A rear cross key 35 extends transversely 55 of the draft sills 10 and through suitable apertures 10^a therein, also through the aperture 30^b in the member 30, the ends projecting on either side of the draft sills 10. One end 35^a is downwardly turned to prevent its withdrawal, as shown in Fig. 9, 60 and the other end is apertured at 35^b to permit the insertion therethrough of a headed pin 35^c, a cotter-pin 35^d being utilized therewith to also prevent withdrawal of the key 65 35 after assembly of the structure.

The draw-bar 20 is provided with a cross aperture 20^a extending transversely thereof and partially surrounding said aperture. At the sides of the draw-bar 20 are flanges 20^b of maximum width at the portion nearest the upper end of the draw-bar 20 and tapering down to the surface of the draw-bar as shown in Fig. 7. A strengthening rib or flange 20^c extends from the highest portion of the flange 20^b to the surface of 75 the draw-bar to enhance the strength of said flange.

In the form of draft rigging shown, the coupler butt or draw-bar contacts with a front follower member 10^b, similar to follower 15^a, for transmission of buffing stresses to such draft rigging as is customary. In suitable apertures in the side sills 10 are mounted the front draft lug members 40, shown in perspective in Fig. 8, and provided with surface riveting flanges 40^a constructed for riveting or suitable attachment to the side sills. Projecting outwardly from one face of the flanges 40^a is the flange 40^b surrounding the aperture 40^c and of 85 sufficient size as to project some distance through the side sills 10 and closely fit the apertures provided therefor in such side sills. The draft lugs proper, 40^d, are formed integral with the members 40 at top 95 and bottom thereof at one end, a space 40^e being provided therebetween. Strengthening ribs or flanges 40^f extend from the draft lug portions 40^d to the face of flange 40^b. Partially surrounding the aperture 40^c in 100 the member 40 is a triangular flange 40^g extending from the face of flange 40^b to its maximum inward projection at one end of the aperture 40^c, this flange 40^g and the draft lug flanges 40^b being so arranged as 105 to leave a space between their points of origin at the flanges 40^a for a purpose to be hereinafter described.

A front cross key 35', similar to key 35 and similarly held in place, extends through 110 the apertures in draft lug members 40 and aperture 20^a in the draw-bar 20, projecting a suitable distance on either side of the draft sills 10, as shown in Fig. 1, for example. When properly assembled, the 115 flanges or collars 20^b of the draw-bar 20 project axially along the cross key 35' some distance on either side beyond the top of flanges 40^b of the draft lug members 40, as shown in Fig. 2. When, as frequently occurs in present day freight or passenger hauling, an unusual shock or compression is transmitted to the draft gearing 15 through the medium of coupler draw-bar 20, this shock may be of sufficient power to compress the draft rigging 15 and transmit considerable of the shock to the side sills 120 through the medium of the cross key 35'. This shock, in my construction, will be received by the member 40 and increased con- 125 130

tacted surface therefor will be provided by the flange 40^a; since, when the key 35' is in contact therewith, the contact of draw-bar flanges 20^b overlaps the contact of flanges 40^c, as will be obvious from an examination of Fig. 1. Any bending or shearing stress that the key would be subjected to were such flanges not present, is obviated, and the key receives substantially only a compression stress which may be taken care of by suitably designing said key. In assembling this structure the draw-bar 20 is moved into position underneath the side sills and front draft lug member 40 in such wise that it can be lifted into position preliminary to inserting the key 35' therethrough, the spacing of the origin points of flanges 40^c and 40^a permitting this lifting and positioning movement.

As in the structure of my previous patent, side links or arms 45 extend between the keys 35 and 35' outside of the sills 10, being held thereon against accidental removal by means of the pins 35^c and down-turned ends 35^a of the keys themselves. These links are apertured at front and back as indicated by numeral 45^a—see Fig. 9—these apertures or slots being of such size that when the draft rigging is in normal position, as indicated in Figs. 2 and 3—in which position it will fill the space between the front and rear draft lugs—the links will approximately contact with the front of the front key 35' and will be slightly out of contact with the rear of the rear key sufficient to permit the necessary amount of coupling travel before the draft gear commences to operate, and after such necessary coupler travel has been utilized further pull on the draw-bar 20 will be transmitted to key 35' on the arms 45 to the rear key 35, which in turn will move the follower member 30 forwardly of the side sills to compress the draft gear. It is obvious that such arms 45 are not suited to receive compression stresses, and since the draft gear receives buffing strains directly from the draw-bar itself, the slots 45^a are made of sufficient length to permit inward or buffing travel of the front key 35' a distance equal to the limit of gear travel, at which limit key 35' will contact with the draft lug members 40 so that no compression or other stress will be transmitted through the links 45 to the rear key 35, as will be obvious. I thicken the ends 45^b of the links or arms 45 around the ends of the slots 45^a to provide additional strength outwardly of the keys so as to prevent the destruction of said links by the keys when pulling strain has been transmitted therebetween. Furthermore, by constructing the slots 45^a of the same length at each end of the links 45 they are interchangeable, and it would be impossible for ignorant workmen to assemble them in an incorrect manner.

It is highly desirable to maintain the arms 45 in parallel relation with respect to the direction of their movement and the side sills 10, and also to maintain them out of contact with the heads or rivets, or the like, utilized to secure the front and rear draft lug members to the side sills. The projecting flange 40^b of the member 40 serves this purpose at the draw-bar end of the rigging, and I utilize spacing-washers 50, or the like, surrounding the key 35 at the rear end of the rigging, such spacers being located between the link members 45 and the draft sills 10, as shown in Fig. 1.

It will be apparent that my invention is susceptible of modifications and improvements, and I do not wish to be restricted to the form shown and described, except as defined in the appended claims.

What I claim is:

1. In combination, a coupler having a butt, a removable key housing operatively attached thereto, a key extending through said housing, and a draft lug carrying member, said housing having a surface normally lying substantially flush with said draft lugs whereby buffing shocks will be received jointly by said lugs and housing face.

2. In combination, a coupler having a butt, a removable key housing operatively attached thereto, a key extending through said housing, and a draft lug carrying member, said housing having a surface normally lying substantially flush with said draft lugs whereby buffing shocks will be received jointly by said lugs and housing face, said face being recessed to partially surround said lugs.

3. In combination, a coupler having a butt, a removable key housing operatively attached thereto, a key extending through said housing, and a draft lug carrying member, said housing having a surface normally lying substantially flush with said draft lugs whereby buffing shocks will be received jointly by said lugs and housing face, said face being cut away at its corners to partially surround said lugs.

4. In combination, a coupler having a butt, a key extending therethrough, a movable key housing, a key extending therethrough and operatively attached to said first named key, a draft lug carrying member, said housing having a surface normally lying substantially flush with said draft lugs, and draft gear located between said coupler butt and said housing.

5. In combination, draft sills, a coupler having a butt located between said draft sills, a key extending through said butt and sills and movable relative to the latter, a draft gear located between said sills, means to transmit draft from said key to said gear, and means carried by said sills and said coupler butt to prevent shearing of said

key when the latter is at its limit of draft movement.

6. In combination, draft sills, a coupler having a butt located between said draft sills, a key extending through said butt and sills and movable relative to the latter, a draft gear located between said sills, means to transmit draft from said key to said gear, and members located adjacent the limit of draft travel of said key to provide increased contact surface therefor, said coupler butt being provided with outwardly extending portions engageable with said key and extending beyond the inner ends of said first 15 named means.

7. In combination, a coupler having a butt, a key extending therethrough, a draft gear, means to transmit draft from said key to said gear, and means to limit the movement of said key, said means comprising a draft lug carrying member and inwardly projecting portions engageable by said key, said coupler butt having means coacting with said member to prevent shearing of said key.

8. In combination, a coupler having a butt, a key extending therethrough, a draft gear, means to transmit draft from said key to said gear, and means to limit the movement of said key, said means comprising a draft

lug carrying member and inwardly projecting portions engageable by said key, said coupler butt having means coacting with said member to prevent shearing of said key, said last named means comprising portions 35 outwardly extending from said coupler butt.

9. In combination, draft sills, a coupler butt located therebetween, and a key extending through said butt, said sills being slotted to prevent relative movement of said 40 key, said sills being provided with flanges located at one end of said slots, said coupler butt being provided with extended portions on the opposite side of said key whereby when the same is at one end of said slots 45 shearing will be prevented.

10. In combination, draft sills having slots therein, a coupler butt located therebetween, a key extending through said coupler butt and said slots, and key engageable flanges at one end of said slots extending inwardly of said sills, said coupler butt being provided with portions extending outwardly from the sides thereof and beyond the inner ends of said flanges and at the opposite side of said key with respect thereto.

In testimony whereof, I have subscribed my name.

GEORGE C. MURRAY.
